UNITED STATES PATENT OFFICE.

JULIUS OTTO VON STETTEN, OF PHILADELPHIA, PENNSYLVANIA, ASSIGNOR TO
PHILADELPHIA METAL DRYING FORM COMPANY, OF NEW CASTLE, DELA-
WARE, A CORPORATION OF DELAWARE.

DESIGN FOR A HOSIERY-DRYING FORM.

55,733.

Specification for Design.

Patented July 6, 1920.

Application filed April 2, 1919. Serial No. 287,085. Term of patent 14 years.

To all whom it may concern:

Be it known that I, JULIUS OTTO VON STETTEN, a citizen of Austria, residing in the city and county of Philadelphia and State of Pennsylvania, have invented a new, original, and ornamental Design for a Hosiery-Drying Form, of which the following is a specification, reference being had to the accompanying drawing, which forms a part thereof.

Figure 1 is a perspective view, and Fig. 2 an enlarged cross-sectional view, of a form embodying my design.

The particularly distinctive features of the design are that the flat faces and beveled borders are distinctly differentiated in ap-

pearance; the flat faces, although approximately smooth, have a relatively dull or dead finished surface, while the borders have a relatively reflective surface, thereby imparting to the form an attractive and ornamental appearance.

I claim—

The ornamental design for a hosiery drying form, as shown and described.

In testimony of which invention, I have hereunto set my hand, at Philadelphia, Pa., on this first day of April, 1919.

JULIUS OTTO VON STETTEN.
